(57) CLAIM

The ornamental design for a crutch pocket set as shown and described.

DESCRIPTION

FIG. 1 is a front view of a crutch pocket set showing my new design;

FIG. 2 is a rear view of the crutch pocket set;

FIG. 3 is a left side view of the crutch pocket set;

FIG. 4 is a right side view of the crutch pocket set;

FIG. 5 is a top view of the crutch pocket set;

FIG. 6 is a bottom view of the crutch pocket set; and,

FIG. 7 is a top front side perspective view of the crutch pocket set.

The broken lines on the crutch pocket set indicate stitching forming no part of the claimed design or borders of unclaimed portions of the design. The broken lines not on the crutch pocket set are illustrative of environmental structure forming no part of the claimed design.
